ATTORNEY.

UNITED STATES PATENT OFFICE.

OSCAR KLOOWER, OF PHILADELPHIA, PENNSYLVANIA.

DOOR ATTACHMENT.

1,036,646.

Specification of Letters Patent. Patented Aug. 27, 1912.

Application filed November 2, 1910. Serial No. 590,281.

To all whom it may concern:

Be it known that I, OSCAR KLOOWER, a citizen of the United States, residing in Philadelphia, county of Philadelphia, and 5 State of Pennsylvania, have invented a certain new and useful Door Attachment, of which the following is a specification.

The principal object of the present invention is to provide an attachment for doors 10 of theaters, lecture rooms, churches, offices and similar places, whereby said attachment may be shifted to prevent persons from entering the place in question but will allow of easy exit of persons desiring to leave the 15 place in question.

A further object of the present invention is to provide an attachment of the class described, which may be shifted, so as to permit a door to be opened from either side.

20 A still further object of the present invention is to provide a device for locking said attachment, whereby the same may be relatively locked to shifted position and to provide auxiliary means for permanently 25 locking the device to shifted position.

Other objects of the present invention relate to the providing of general details of construction and arrangement of parts as will hereinafter more fully appear.

30 The invention consists of the improvements hereinafter described and finally claimed.

The nature, characteristic features and scope of the invention will be more fully 35 understood from the following description taken in connection with the accompanying drawings forming part hereof and in which:

Figure 1, is a fragmentary view of a door in cross-section, illustrating the shiftable attachment of the invention in application thereto, Fig. 2, is a view in front elevation of Fig. 1, Fig. 3, is a view in elevation looking at the rear of the plate illustrated in Figs. 1, and 2.

45 It is very desirable that the entrance doors to theaters, lecture rooms, churches, offices and similar places be closed at certain times to persons desiring to enter such places, but be free for ready exit to persons within 50 such places. To this end, I have designed an attachment whereby when desired, the door exterior will be free of protruding knobs or handles. In other words, I have designed a shiftable element equipped with 55 a pair of knobs, so arranged that when desired the attachment may be shifted so that

the knob upon the door exterior comes flush with and does not protrude from the said door exterior.

In carrying out the invention, use is made 60 of generally rectangular metallic or other plates 1, and 2, which may be secured to the door 3, by means of screws or the like 4. Passing through the plates 1, and 2, and the door 3, is a shiftable element 5, of circular 65 cross-section. One end of this shiftable element 5, that is the end corresponding to the door exterior is equipped with a disk-like knob or handle 6. This knob 6, may be formed integral with the shiftable element 70 5, or be otherwise secured thereto, and is beveled as at 7, so as to seat itself within the counter-sunk portion 8, of the plate 2, when in the position shown by full lines in Fig. 1. When in this position, obviously 75 a person desiring to open the door 3, from the outside can find no handle or knob by which to pull open the door. In this connection it will be understood that a door check or similar device not shown in the 80 drawings or forming part of this invention is present, for normally keeping closed the door.

A description will now be given of the device for relatively locking the shiftable 85 element 5, as above described.

Shiftably mounted upon the inside of the plate 1, see Figs. 1, and 3, is a spring controlled bolt 9, the upper end of which passes through a keeper or guide 10, and the lower 90 end of which is provided with a knob or handle 11, which protrudes through a slot 12, in said plate 1, from the inside of the door. The shiftable bolt 9, is adapted to register with slots 13, and 14, upon the bottom of the shiftable member 5, and when the said bolt 9, registers with the slot 14, the knob 6, is flush with the plate 2. Should it be desired to permanently lock the bolt 9, with either of the slots 13, or 14, of the 95 shiftable member 5, the same may be accomplished by placing a key in the keyhole 15, of the plate 1, and shifting the bolt 16, of the lock 17, into the position shown by dotted lines in Fig. 3. In other words, the bolt 16, is shifted into engagement with the bolt 9. When in this position, should the bolt 9, be registering with the slot 13, of the shiftable member 5, the knob 6, upon the door exterior and the knob 18, upon the door interior will be in the position shown 100 by dotted lines, in Fig. 1, and the door 105 110

would present the appearance of being equipped with an ordinary pair of handles or knobs. As clearly illustrated, the plate 1, is provided with a key 19, and the shiftable member 5, with a key-way 20, to prevent said shiftable member 5, from turning. To prevent the shiftable member 5, from being shifted too far to the right from Fig. 1, it is provided with a collar 21, which is adapted to abut against the plate 1, when the slot 13, comes into alignment with the vertically shiftable bolt 9. The knob or handle 18, may be secured to the shiftable member 5, by means of a screw or the like 22.

It is thought, that the operation of the above described door attachment will be clearly understood without resorting to a further description thereof. It may be further remarked that the above described door attachment is applicable to all doors where it is desired to prevent persons from entering and yet being free to permit of ready exit. This is particularly true to exit doors to fire escapes. In such cases, while it is desirable that a person from the outside cannot open said exit doors that the said door be free of all locks or bolts for providing ready exit. By the above described device, while the door is not locked, it positively prevents unauthorized persons from entering a building.

What I claim is:

1. An attachment adapted for application to a door comprising an endwise shiftable element extending entirely through said door and equipped at each end with a door knob, the outer face of one of said door knobs being arranged to come flush with the outer surface of said door and means for holding said element in shiftable position.

2. An attachment adapted for application to a door comprising an endwise shiftable

element equipped with knobs one of which is capable of coming flush with the door surface, means for preventing said element from turning, and means for preventing said element from being shifted.

3. An attachment adapted for application to a door comprising an endwise shiftable element equipped with knobs one of which is capable of coming flush with said door surface, means for preventing said element from turning, means for holding said element against shifting and means for positively locking said element against shifting.

4. An attachment adapted for application to a door comprising an endwise shiftable non-turnable element equipped with knobs one of which is of disk-like-shape, a pair of plates for said door one of which is counter-sunk to receive the disk-like knob and a vertically shiftable spring controlled bolt for coöperating with said shiftable element for holding the same in shifted position carried by the other plate.

5. An attachment adapted for application to a door comprising an endwise shiftable element equipped with knobs one of which is disk-shaped, a pair of plates for said door through which said element moves one of said plates being counter-sunk to receive said disk-like knob and the other plate having keyed relation with said element, a vertically movable spring-controlled bolt carried by the other plate, said bolt being adapted to coöperate with slots in the shiftable element for relatively locking the same and means for positively locking said element against shifting.

In testimony whereof, I have hereunto signed my name.

OSCAR KLOOWER.
